Primary Examiner — Dana K Weiland*Assistant Examiner* — Messina L Smith(74) *Attorney, Agent, or Firm* — Carter, DeLuca & Farrell LLP; George Likourezos**(57) CLAIM**

The ornamental design for a live chords midi machine, as shown and described.

DESCRIPTION

FIG. 1 is a perspective view of a live chords midi machine showing the new design;

FIG. 2 is a first side view thereof;

FIG. 3 is a second side view thereof;

FIG. 4 is a third side view thereof;

FIG. 5 is a fourth side view thereof;

FIG. 6 is a top view thereof; and,

FIG. 7 is a bottom view thereof.

The features of the live chords midi machine shown in broken lines do not form a part of the claimed design.
